UNITED STATES PATENT OFFICE.

JASPER DERRY, OF MEDFORD, MASSACHUSETTS, ASSIGNOR TO ANDREW TERKELSEN,
OF BOSTON, MASSACHUSETTS.

WRAPPING MACHINE.

Application filed August 22, 1923. Serial No. 658,767.

This invention relates to wrapping machines of the general type shown and described in an application for Letters Patent filed June 21, 1921, by George W. Prouty,

5 Serial No. 479,410, and adapted primarily for wrapping annular objects, such, for example, as automobile tires, coils of wires, etc.

In a machine of this type the object to be wrapped is supported by a pair of rollers which are rotated at constant speed to advance the work through an annular shuttle which is located between said rollers and which is rotated in a plane transverse to the direction of movement of the work to apply thereto helical windings of a continuous strip of wrapping material. In the machine shown in said prior application the shuttle is vertically adjustable in its plane of rotation to centre the same with respect to the article wrapped thereby adapting the machine to the wrapping of articles of different sizes. It is desirable that the successive windings of the strip overlap a constant amount irrespective of the thickness of the article wrapped, and, in order to accomplish this result, it is necessary that the windings be applied to an article of relatively small thickness at a greater pitch inclination than those applied to an article of relatively great thickness. The inclination at which the strip is wound is determined by the direction in which the strip is led from the shuttle to the work, and in accordance with the present invention the angle at which the strip engages the work is automatically determined by the thickness of the work itself, while means are provided whereby the portion of the work being wrapped is brought substantially parallel to the axis of the shuttle, so as to cause both edges of the strip to engage the work with equal pressure and prevent undue strain upon either, this result being accomplished simultaneously with the adjustment of the shuttle in accordance with the size of the article wrapped as above explained.

The foregoing and other objects of the invention, together with means whereby the same may be carried into effect, will best be understood from the following description of one form or embodiment thereof illustrated in the accompanying drawings. It will be understood, however, that the particular construction described and shown has been chosen for illustrative purposes merely,

and that the invention, as defined by the claims hereunto appended, may be otherwise practiced w/out departure from the spirit and scope thereof.

60 In said drawings:

Figs. 1 and 2 are front and side elevations, respectively, partly in section, of a wrapping machine embodying the invention.

Fig. 3 is a diagrammatic view illustrating the adjustment of the machine for work of 65 different sizes.

Figs. 4 and 5 are fragmentary detail views showing tires of different sizes wrapped with helically wound strips of wrapping material whose inclination or pitch in each case is 70 such as to cause the successive wrappings to overlap a constant amount.

Fig. 6 is a top plan view and Fig. 7 a face view of the shuttle, showing in full and dotted lines respectively, the wrapping strip 75 led therefrom to a relatively large article and to a relatively small article.

The frame of the machine comprises a base 15 and a yoke 16 which is pivotally mounted on a shaft 17 journalled in an upright 80 18 rising from the base 15. The yoke 16 is provided with guide rollers 19 for an annular shuttle 20 which is rotated by a driving member in the form of a friction disk 21 secured to the shaft 17 and driven through connections (not shown in detail) from an electric motor 23 supported on the base 15. The tire or other work W to be wrapped is supported by rollers 24 and 240 which are driven through connections, generally indicated at 85 25, from the motor 23, the arrangements being such that the work W will be turned relatively slowly with respect to the speed of rotation of the shuttle 20. The yoke 16 may be adjusted, by means of a handle 22, about 25 the axis of the shaft 17, to centre the shuttle 20 with respect to annular objects of different sizes, said yoke being counterbalanced by a spring 27 and being locked in adjusted position by means of a clasp 28 to an upright 29 rising from the base 15. The wrapping material, preferably in the form of a continuous strip S of paper, is herein shown as supplied from a roll 30 on the shuttle 20, said paper passing from said roll through a 100 105 folding device 33, and thence about a guide stud 36 to the work W.

From the foregoing the nature, location and function of the parts referred to will be sufficiently understood for the purposes of the 110

present case. With the exception of those hereinafter described, and in so far as the others enter into combination therewith, as pointed out in the claims, these parts are not involved in the present invention and may be of any suitable construction and arrangement.

As in another application, Serial No. 637,658, filed May 9, 1923, by George W. Prouty, the work supporting rollers 24 and 240 are carried respectively by standards 40 and 50 rising from the base of the machine, and each of said rollers has splined thereto a pair of sliding collars 45 which may be adjusted toward and from each other on the roller to cause them to engage and laterally position or center objects of different thickness. Each of said collars is provided with a circular flange 6 having an annular peripheral groove which is engaged by pins carried by the upright arm of bell cranks 49. The bell cranks 49 are arranged in pairs, there being a pair corresponding to each roller. The corresponding bell cranks of the several pairs are carried by shafts 54 journalled in suitable bearings on the standards 40 and 50, while the laterally extending arms of the bell cranks of each pair are formed with interengaging parts constituting, in effect, intermeshing gear segments. One of the shafts 54 is provided with an arm 55 having an angularly offset end formed with a longitudinal slot to receive a pin 56 secured to and projecting from the yoke 16. When said yoke is adjusted in accordance with the size of the work, in order to center the shuttle 20 with respect to said work, the pin 56 will cause the arm 55 to move a predetermined amount, thereby also adjusting the collars 45 on the rollers in accordance with the size of the work, as more fully explained in said application Serial No. 637,658.

In accordance with the present invention, means are also provided for varying the angle at which the strip S engages the work, as it is wound thereabout, in accordance with the thickness of the work. In Figure 3 the shuttle 20 is shown in full and dotted lines respectively as adjusted into vertical positions in which it will be centered with respect to a relatively large tire or similar annular article W² and a relatively small tire or article W¹, respectively. It is desirable that the successive windings of the strip S overlap one another a substantially constant amount irrespective of the thickness of the article wrapped, and by reference to Figures 4 and 5 it will be seen that in order to accomplish this result it is necessary that the strip be wound at a greater inclination on the relatively small tire W¹ than upon the relatively large tire W². Since the rollers 24 and 240 are rotated at a constant speed irrespective of the size of

the work carried thereby this variation in inclination is determined by the angle at which the strip is led from the guide stud 36 to the work. To this end, as shown, the stud 36 is disposed at a slight inclination to the face of the shuttle, and to the path of the strip, so as to twist the latter to a certain extent, the arrangement being such, as shown in Fig. 6, that the farther the strip is wrapped about said stud, the more the strip will be twisted and the greater will be the angle with the face of the shuttle at which said strip is guided to the work. Thus, as shown in Fig. 7, the strip in passing from the stud to the relatively small tire W¹, will pass about a greater portion of the periphery of the stud than when passing therefrom to the relatively large tire W², and will therefore be led to the tire W¹ at a greater angle than to the tire W², as shown in Fig. 3, thereby causing the same to be wound upon the tire W¹ at a greater inclination than upon the tire W².

By reason of this difference in inclination at which the strip is led from the shuttle to the work, said strip engages the tire W¹ at a greater distance from the shuttle than the tire W². It is desirable, however, in order to prevent undue strain upon either edge of the strip, that the part of the work being wrapped be as nearly as may be coaxial with the shuttle. Thus, in the case of an annular article, such as a tire, it is desirable that the middle of the strip engage the outer side of the tire at the point of tangency of the latter with a line (T¹ or T², Fig. 3) drawn parallel to the axis of the shuttle. For the reasons above stated, this point must be positioned at a greater distance from the shuttle in the case of the relatively small tire W¹ than in the case of the relatively large tire W². This, in the construction shown, is accomplished by raising or lowering the work supporting roller 240 with respect to the roller 24, said roller 240 being adjusted into a relatively higher position for the large tire W² than for the small tire W¹. This causes the large tire W² to be relatively tilted toward the shuttle with respect to the position of the small tire W¹, as shown in Figure 3, thereby bringing the lowermost point of said relatively large tire, at which point the strip engages the tire, closer to the shuttle than in the case of the smaller tire.

In accordance with the construction herein shown, the uprights 50 are connected into a unitary structure by a cross web 60, and are formed with lugs 61 having aligned openings to receive vertical posts 62 carried by the base, whereby said standards are guided for vertical movement. The transverse web 60 is formed on its under side with a lug 63 which passes through an opening in the base and rests upon a lever 64 pivoted at 65 to

a lug 66 secured to the inner side of one of the depending portions 67 of the base. The lug 63 is preferably connected with the lever 64 by a screw 69 in threaded engagement with said lug and passing through a slot in said lever. The free end of the lever 64 is connected by a link 68 with the yoke 16. In order to permit this relative adjustment of the standards 40 and 50, the shafts 54 are each formed in two sections connected by universal joints 70.

With this construction it will be seen that when the yoke 16 is adjusted vertically to center the same with respect to the work, the work supporting roller 240 will also be automatically adjusted into the proper vertical position to cause the strip S to be wound in the manner suitable for the particular object being wrapped. Thus, for example, if the shuttle 20 be lifted from the position shown in dotted lines in Figure 3 into the position shown in full lines therein, in order to center the same with respect to the tire W², the work supporting roller 240 will also be lifted from the position shown in dotted lines into that shown in full lines, causing the strip S to engage the tire at a point relatively nearer to the shuttle in accordance with the requirements. It will also be seen that during this operation the collars 44 will be simultaneously adjusted in accordance with the size of the work in order properly to center the latter with respect to the shuttle. It therefore follows that a simple vertical adjustment of the shuttle yoke of such a character as to center the shuttle with respect to the work, as can readily be determined by inspection, will be automatically accompanied by such other adjustments of the machine as may be necessary in order properly to wrap the object for which the shuttle is adjusted.

Having thus described my invention, I claim:

1. In a machine of the character described, a rotatable shuttle, a plurality of work supporting rollers, and means whereby said shuttle and at least one of said rollers may be simultaneously adjusted to adapt the machine to work of different sizes.

2. In a machine of the class described, a

rotatable shuttle, an adjustable shuttle supporting yoke, a plurality of rotatable work supporting rollers, at least one of said rollers being adjustable to adapt the machine to work of different sizes, and means operated by said yoke for adjusting said roller. 55

3. In a machine of the class described, a rotatable shuttle, an adjustable shuttle supporting yoke, a plurality of work supporting rollers, standards by which said rollers are carried, one of said standards being vertically movable, a lever for supporting said movable standard, and a link connecting said lever and yoke. 60 65

4. In a machine of the class described, a rotatable shuttle, an adjustable shuttle supporting yoke, a plurality of rotatable rollers for supporting the work to be wrapped, at least one of said rollers being adjustable to 70 adapt the machine to work of different sizes, longitudinally slideable collars on said rollers, and means operated by said yoke for simultaneously adjusting said adjustable roller and said collars. 75

5. In a machine of the class described, a rotatable shuttle through which the work is adapted to be moved, an adjustable yoke for supporting said shuttle and adapted to be moved to center the shuttle with respect to the work, a plurality of rotatable rollers for supporting and moving the work, at least one of said rollers being bodily adjustable to adapt the machine for work of different sizes, longitudinally slideable collars on said 85 rollers, said collars being secured to said rollers so as to revolve therewith, and mechanism operated by said adjustable yoke for adjusting said roller and moving said collars toward and from each other when said yoke 90 is adjusted.

6. In a machine of the class described, the combination of supporting means for the work to be wrapped, a rotatable shuttle for wrapping a strip around said work, means carried by the shuttle for controlling the inclination at which the strip is led to the work, and a common means for adjusting the shuttle relatively to the work and for adjusting the work relatively to the strip. 95 100

In testimony whereof I affix my signature.
JASPER DERRY.
